UNITED STATES PATENT OFFICE

GEORG HAYN, OF KASSEL, GERMANY

COAL DUST FURNACE

Application filed December 26, 1928, Serial No. 328,586, and in Germany January 31, 1928.

The invention relates to coal dust furnaces more particularly those intended for locomotives and having a burner that has the shape of a spray nozzle.

5 One of the most difficult problems in applying coal dust furnaces to locomotives is the realization of a complete combustion under the peculiar conditions existing in locomotives, that is, the adaptation, as far as possible, of the furnace to the usual design of the locomotive combustion chamber. In comparison with stationary furnaces the main difficulty with locomotives resides in the fact that in the latter the combustion 10 chamber is very small, whilst on the other hand the coal dust particles for their complete combustion require a certain minimum time, minimum path, and a minimum volume of the combustion chamber. These conditions can be combined to a minimum value 15 that must not be reduced, only if the other conditions are the most favorable for combustion.

To this end it is necessary that the coal 20 dust particles are mixed with a sufficient quantity of air previous to leaving the burner, in order that the oxygen required for the combustion may be immediately at the disposal of every coal dust particle. Conveniently a portion of the combustion air, in the 25 most of cases the greater part thereof; this depending upon the desired division of this air, is added to the coal dust before the latter enters the combustion chamber. Furthermore, a rapid pre-heating of the coal dust-air 30 mixture after its entrance in the combustion chamber has to be provided for, by radiation, best from the hot brickwork, in order to have the coal dust ignited as soon as possible after 35 having entered the combustion chamber, to fully utilize the latter. This requirement may be met by a suitable distribution of the mixture in the combustion chamber, by employing one or more burners that are so constructed 40 that they subdivide the mixture into a great number of partial jets and thus increase its surface. With this arrangement individual short thin flames are formed that unite into a round flame and completely fill 45 the combustion chamber without sharply

striking the walls, a premature destruction of the latter thus being avoided. Finally, the determination of the average temperature of the fire box is of importance, as due to the small size of this chamber in locomotives only a determined gas volume can be 55 lodged therein, which however increases with increasing temperature. A lowering of the temperature in the fire box and thus a reduction of the gas volume therein however results in an increase of the specific load of the fire box, that is an increase of the quantity of heat supplied in the time unit and space unit of the combustion chamber.

60 If all these favorable conditions are to be fulfilled, it is necessary to have the igniting zone of the coal dust situated close to the burner head which thereby in a very high degree is exposed to the action of the heat radiated by the flame. To prevent therefore 65 premature destruction of the burner, a water cooling arrangement has been provided with known furnaces of this type. This provision however involves both a very complicated construction and an undesirable increase of weight, so that with other designs 70 this water cooling has been replaced by an air cooling arrangement. To this end a portion of the combustion air is supplied to the combustion chamber as so-called additional 75 air through passages that surround the coal dust supplying tube, this cold additional air causing the temperature at the burner head to be held within admissible limits.

80 The known constructions hereinbefore described however do not constitute the simple solution of the problem to be aimed at. Now the object of my present invention is a coal dust burner that to the largest possible extent fulfills the required conditions as to 85 simple construction, sufficient cooling effect and other requirements. This object is obtained by constructing a burner which has a front plate comprising a large number of closely spaced small nozzle-shaped holes. The burner body proper thereby lies entirely outside the combustion chamber and being thus cooled by the outer air remains comparatively cold even with the highest effect of the 90 burner, while the nozzle plate which is ex- 95

100

posed to the radiation of the flame is cooled by the air that conveys the cold coal dust-air mixture entering the combustion chamber. As in this manner the quantity of air passing 5 through the nozzle plate is very abundant, this air conveniently being not only coal dust conveying air but also in part combustion air, the temperature of the nozzle plate is held within such limits that this sensitive burner 10 part is not endangered.

Furthermore, the flaring shape of the nozzles or openings of said burner plate has a particularly favorable influence upon the cooling of this plate. For, by the high speed 15 of the cooling means, that is of the conveying and combustion air, at the narrowest or most constricted place of the nozzle plate not only the necessary reduction of the temperature of this plate is obtained, but also the flame is 20 prevented from striking back into the burner body, since it is possible to determine by suitably shaping the nozzles the speed of the coal dust-air mixture so as to always be higher than the speed of ignition of the mixture. By 25 conically enlarging the nozzles toward the combustion chamber, whereby the speed of the mixture is reduced, the condition is fulfilled which is in opposition to the above-indicated requirement, that the speed of the 30 constituents of the mixture should be as low as possible to obtain a short length of flame.

In order to allow my invention to be more easily understood, a preferred embodiment of the same is illustrated by way of example 35 in the drawing which accompanies and forms part of this specification. In this drawing

Figure 1 is a longitudinal section through the combustion chamber of a coal dust fired locomotive.

Figure 2 is the section on line I—I of Figure 1, seen in the direction of the arrows and on an enlarged scale.

The combustion chamber of the coal dust furnace illustrated consists of a fire box *a* of 45 usual description and a bottom box *b* fitted with suitable brickwork. In the rear, vertical wall of box *b* are arranged symmetrically to the longitudinal middle plane of the engine two burners *c*¹ and *c*². Each of these burners 50 substantially consists of a hollow truncated conical portion, the smaller rear face of which is connected to a suitable mixer *f* for the coal dust-air mixture. These burners are designed as spray nozzles, that is their heads are 55 formed by a rose plate *d*, this plate simultaneously forming a portion of the wall of box *b*. In the plates *d* are provided close together nozzle-shaped holes *e* which may be circular, slotted or of any other suitable shape and 60 through which the coal dust-air mixture is blown into the combustion chamber. For the sake of clearness in Figure 2 these holes *e* are shown somewhat greater than they really are. As already mentioned the intimate mixing 65 of the two mixture constituents taking

part in the combustion takes place before the burner proper within the mixer *f* separately provided for each burner and not shown in detail.

The function of the burner and the manner in which it is cooled will be understood from the foregoing without further explanation. Owing to the brickwork being restricted to a minimum extent, the temperature of the fire box can be lowered as mentioned above, because a good heat transmission is obtained by the non-lined water-cooled walls of the fire box. To inspect or repair the burners, they need only be disconnected from the wall of the box and can then be removed from their seats. To this end they are fixed on the wall from outside.

Instead of being arranged on the wall of said lower box, as in the embodiment illustrated, the burners may be disposed at any other place of the lower box or fire box, according to special constructive points of view or conditions of service. Besides as a matter of course more or less individual burners may be provided for instead of the two burners illustrated, as circumstances may require, without deviating from the scope of the invention.

What I claim and desire to secure by Letters Patent, is:—

1. In a coal dust firing installation, a common coal dust and air supply conduit, a burner in which said conduit terminates, said burner having a face plate provided with a large number of small flaring discharge openings adapted to discharge the mixture of coal dust and air, said openings being closely spaced with their axes parallel to the axis of the burner.

2. In a coal dust firing installation, a common coal dust and air supply conduit, a burner in which said conduit terminates, said burner having a face plate provided with a large number of small discharge openings adapted to discharge the mixture of coal dust and air, said openings being closely spaced with their axes parallel to the axis of the burner, and said openings flaring in the direction of flow, thereby permitting expansion of the mixture and consequent reduction in velocity as it flows through the plate.

The foregoing specification signed at Frankfort-on-the-Main, Germany, this 12th day of December, 1928.

GEORG HAYN.
